US00D602865S

(12) **United States Design Patent**
Zhang

(10) **Patent No.:** **US D602,865 S**
(45) **Date of Patent:** **** Oct. 27, 2009**

(54) **BATTERY CONNECTOR**

(75) Inventor: **Hong Tu Zhang**, Tu-Cheng (TW)

(73) Assignee: **Cheng Uei Precision Industry Co., Ltd.**, Taipei Hsien (TW)

(**) Term: **14 Years**

(21) Appl. No.: **29/311,443**

(22) Filed: **Mar. 18, 2009**

(51) **LOC (9) Cl.** **13-03**

(52) **U.S. Cl.** **D13/120**

(58) **Field of Classification Search** **D13/118-121, D13/133, 146-147, 184, 199; 439/83, 108, 439/166, 500, 577, 630, 660, 680, 700, 773.1, 439/862**

See application file for complete search history.

(57) **CLAIM**

The ornamental design for a battery connector, as shown and described.

DESCRIPTION

FIG. 1 is a perspective view of a battery connector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the battery connector showing my new design.

The broken lines in the Figures are for illustrative purposes and form no part of the claimed designs.

1 Claim, 8 Drawing Sheets

FIG. 1

FIG. 2

FIG. 3

FIG. 4

FIG. 5

FIG. 6

FIG. 7

FIG. 8
